ATTORNEYS.

UNITED STATES PATENT OFFICE.

STANLEY W. WIDNEY, OF CHICAGO, ILLINOIS.

SEAT-PAD.

1,280,344.

Specification of Letters Patent.

Patented Oct. 1, 1918.

Application filed January 6, 1917. Serial No. 140,871.

To all whom it may concern:

Be it known that I, STANLEY W. WIDNEY, a citizen of the United States, residing at Chicago, county of Cook, and State of Illinois, have invented certain new and useful Improvements in Seat-Pads, of which the following is a specification.

This invention relates to seat pads for chair bottoms and the like, and has reference 10 more particularly to improvements in that type of seat pads which consist of a piece of felt or like material having the general shape of the chair bottom and substantially covering the latter. One form of seat pad of 15 this type which is now quite extensively used is secured to the chair bottom by a series of straps projecting from the edges of the pad and carried over the edges of the chair bottom and tacked to the underside of the latter. This method of fastening the pad renders 20 the latter practically immovable, with the result that the movements of the occupant of the chair on the chair bottom produce an undesirable amount of friction 25 between the clothes of the occupant and the pad, which is not only uncomfortable but produces an undesirable amount of wear on the clothes of the occupant. Furthermore, the front straps produce an undesir- 30 able rubbing or chafing on the legs of the occupant when sitting down or moving sideways on the chair bottom. With a view to reducing friction between the pad and the clothes of the wearer it has heretofore been 35 proposed to connect the pad to the chair bottom by means of elastic straps so as to permit movement of the pad upon the chair bottom with the person of the occupant; but this improvement does not eliminate all of 40 the faults above noted, and, furthermore, such elastic fastening devices are short lived, and do not permit the pad to be readily de- 45 tached for purposes of cleaning.

It is the general object of the present invention to provide a chair pad which, by reason of its peculiar attachment to the chair bottom, shall be capable of moving on the latter with the person of the occupant, thus eliminating frictional wear on the clothes of 50 the occupant and preventing the latter from becoming shiny; which shall obviate any discomfort to the occupant by reason of rubbing or chafing on the fastening straps; and which shall be easily and readily detachable for purposes of cleaning or repair. With these objects in view the invention

consists in the improved chair pad and its attaching means substantially as hereinafter described and definitely pointed out in the claims.

In the accompanying drawing I have illustrated my improved pad and its manner and means of attachment to a chair seat, and referring thereto—

Figure 1 is a top plan view of my improved seat pad shown as applied to a chair seat or bottom.

Fig. 2 is an enlarged fragmentary section through the pad, chair bottom and fastening means on the line 2—2 of Fig. 1.

Fig. 3 is an enlarged fragmentary bottom plan view of the pad illustrating the attaching means.

10 designates my improved pad which may be made of felt, cloth, or any suitable material, and is cut to the general shape and dimensions of the chair seat or bottom 8 which it is designed to serve. In carrying out my invention I dispense with the usual fastening straps or tapes commonly secured 15 to the pad and passed over the edges of the chair bottom and tacked to the underside of the latter, and I secure to the underside of the pad 10 substantially centrally of the rear edge thereof a short strip 11 of leather or 20 other suitable material that is attached at its ends to the pad by rivets 12, or equivalent attaching means. This strip 11 has an elongated longitudinal slit 13 between its 25 attaching ends forming a buttonhole; and 30 the strip is, by means of this buttonhole, passed over the broad substantially flat head 35 14 of a tack 15 that is driven into the chair bottom 8 adjacent to and centrally of the 40 rear edge of the latter, the head 14 thus constituting in effect a button coöperating with 45 the elongated slit or buttonhole 13 of the strip 11.

By the fastening means above described 50 the pad is readily attached to and detached 55 from the chair bottom, and when attached to the latter is capable of a sliding movement thereon not only in a forward and rear direction but also in a sidewise direction, that is amply sufficient to accommodate the 60 corresponding sliding or turning movements of the occupant when seated in the chair without any relative sliding movement 65 between the trousers or skirt of the occupant and the pad, all of the relative movement occurring between the underside of 70 the pad and the chair bottom.

It will thus be seen that my improvement not only eliminates frictional wear between the pad and the clothes of the occupant, but also dispenses with the unsightly and uncomfortable fastening straps of the old construction, and, furthermore, produces a device which can be very quickly attached and detached without the necessity of driving or pulling tacks or similar fastening devices. The pad itself is preferably made of felt and the slitted attaching strip of leather, although it is manifest that other materials may be used if desired and the construction may be otherwise modified in detail within the purview of the appended claims:

I claim:

1. A seat pad for chair bottoms and the like, comprising a pad having the general 20 shape of a chair bottom and adapted to substantially cover the same, and a strip of suitable material secured to the underside of said pad adjacent to its rear edge and provided with means adapting the pad to be detachably secured to a coöperating member located on the top surface of the chair bottom.
2. A seat pad for chair bottoms and the like, provided with a buttonhole adjacent 30 to its rear edge adapting it to be detachably secured to a button on the chair bottom with capacity for sliding movement on the chair bottom.
3. A seat pad for chair bottoms and the

like, provided with an elongated buttonhole 35 adjacent to and substantially centrally of its rear edge adapting it to be detachably secured to a correspondingly located button on the chair bottom with capacity for forward and back and lateral sliding movement on the chair bottom.

4. A seat pad for chair bottoms and the like, comprising a pad having the general shape of a chair bottom, and adapted to substantially cover the same, and a strip of 45 suitable material secured at its ends to the underside of said pad adjacent to and substantially centrally of the rear edge of the latter, said strip having between its secured ends a longitudinal slit or buttonhole adapting the pad to be detachably secured to a correspondingly located button on the chair bottom.

5. The combination with a chair bottom and a headed stud set therein adjacent to 55 and substantially centrally of its rear edge, of a pad to cover said bottom having secured to its underside a strip of suitable material formed with a slit, whereby said pad is adapted to be buttoned to said bottom with 60 capacity for a limited universal edgewise movement on the latter.

6. The combination with a chair bottom and a pad, of means connecting said pad to said bottom at a single point and permitting 65 a limited universal edgewise movement of the pad on the bottom.

STANLEY W. WIDNEY.
